[57] CLAIM

The ornamental design for a paper feeder for electronic
copying machine, substantially as shown.

DESCRIPTION

FIG. 1 is a front, top and right side perspective view of
a paper feeder for electronic copying machine showing
my new design;

FIG. 2 is a perspective view like FIG. 1 with the cover
opened;

FIG. 3 is a front elevational view thereof;

FIG. 4 is a top plan view thereof;

FIG. 5 is a right side elevational view thereof;

FIG. 6 is a rear elevational view thereof; and

FIG. 7 is a left side elevational view thereof.

FIG. 1

FIG. 2

FIG. 3
